UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

SNAP-SWITCH HANDLE.

1,330,628.

Specification of Letters Patent. Patented Feb. 10, 1920.

Application filed July 1, 1916. Serial No. 107,099.

To all whom it may concern:

Be it known that I, FREDERIC P. GATES, a citizen of the United States of America, and residing at Hartford, in the county of 5 Hartford and State of Connecticut, have invented a certain new and useful Improvement in Snap-Switch Handles, of which the following is a specification.

My invention relates to snap switches and 10 particularly to the operating thumb piece therefor, the object of my invention being to provide an inexpensive and efficient operating thumb piece adapted to be permanently secured upon the switch spindle.

15 In the accompanying drawings,

Figure 1 is a plan of a snap switch showing a thumb piece in which my invention is embodied;

20 Fig. 2 is a side elevation of the same partially broken away; and

Fig. 3 is an inverted plan of the thumb piece.

It is desirable in certain installations to have a thumb piece for the snap switch permanently secured to the operating spindle of the switch mechanism instead of merely screwed thereon as is the common practice. 25 The present invention provides a simple and inexpensive construction by which this 30 may be accomplished. The switch here shown is of common type comprising an insulating base 10 upon which the switch mechanism (not shown) is mounted and enclosed by a suitable metallic casing 11. The

35 switch mechanism is operated by the switch spindle 12 around which is coiled the switch spring 13. The usual upward extension of the spindle 12 is provided, as customary, with a threaded area 14, but in the present 40 construction this area is sheared on opposite sides to afford flats 15. The switch handle 16 has at its inner end a boss here formed by a metallic ferrule 17 molded to the body of the switch handle 16 and provided with 45 a non-circular aperture 18 fitting over the upper end of the switch spindle 12 and engaging the flats 15 so as to render the switch spindle non-rotatable with relation to the boss 17. The latter is prevented from swiveling with relation to the handle 16 by flats 19 on the outer faces thereof which are in contact with the molded body of the handle. 50 Recesses in the form of a cross slot 20 at the inner end of the ferrule receive the upturned end 21 of the switch spring in which-

ever position the handle is assembled with relation to the switch spindle. A central bore 22 extending through the handle affords means for the insertion therethrough of the locking thimble 23 which is internally tapped at 24 to engage the threaded end of the switch spindle 12. A cross slot 25 in the head of the thimble 23 permits the latter to be screwed home by means of a screw driver. After the thimble 23 has been secured in place the space above the latter is filled with an insulating composition 26 of any sort, such as wax, thus preventing access to the locking thimble 23 and permanently securing the parts together. 70

Various modifications and details of construction will readily occur to those skilled in the art without departing from what I claim as my invention.

I claim as my invention:—

1. A thumb piece for a snap switch mechanism comprising a boss adapted to be fit over a rotary switch spindle and mechanically engaging the same and means for locking the same against relative rotation of the 80 parts to said spindle to prevent separation of the parts.

2. A snap switch having a rotary actuating spindle with non-circular outer end, an actuating thumb piece having a boss with 85 non-circular bore engaging said spindle to prevent relative rotation of the parts and means for locking said thumb piece and spindle in assembled condition.

3. A snap switch having a rotary actuating spindle with non-circular outer end, an insulating thumb piece having a metallic boss with non-circular bore engaging said spindle to prevent relative rotation of the parts and means for locking said thumb 95 piece and spindle in assembled condition.

4. A snap switch having a rotary actuating spindle with threaded outer end, flats on said outer end, a thumb piece having a boss with an aperture of non-circular contour 100 engaging said flats to prevent relative rotation of the parts, and a locking thimble engaging said spindle to hold the parts in assembled position, together with means for covering said thimble to render the latter 105 inaccessible, for the purpose described.

5. In a snap switch, a rotary switch spindle, a thumb piece having at its inner end a boss recessed to receive a member moving with the spindle and means for locking said

- thumb piece on the spindle, for the purpose described.
6. A thumb piece for a snap switch comprising an insulating body, a non-circular ferrule molded therein, and a non-circular bore for said ferrule adapted to fit over the non-circular end of a switch spindle.
7. A thumb piece for a snap switch comprising an insulating body, a non-circular ferrule molded therein, and a non-circular bore for said ferrule adapted to fit over the non-circular end of a switch spindle, together with a recess in the exposed end of said ferrule to receive the end of a switch 15 spring coiled on the switch spindle.
8. A thumb piece for a switch spindle comprising an insulating button pierced in alignment with the spindle, and a bushing molded in said button and having a non-circular bore through which the spindle passes in assembled position, a locking 20 thimble located in the piercing of said button and seated against said bushing, said thimble being internally threaded to engage the end of the switch spindle projecting beyond said bushing, and insulating material filling said piercing above the thimble to render the latter inaccessible substantially as described.
9. A thumb piece for a switch spindle comprising an insulating button pierced in alignment with the spindle, and a bushing molded in said button and having a non-circular bore through which the spindle passes in assembled position, a locking 25 thimble located in the piercing of said button and seated against said bushing, said thimble being internally threaded to engage
- the end of the switch spindle projecting beyond said bushing, and insulating material 40 filling said piercing above the thimble to render the latter inaccessible substantially as described, together with means associated with said bushing for engaging the end of the switch spring coiled on the switch 45 spindle.
10. A thumb piece for a switch spindle comprising an insulating body, associated means for engaging the switch spindle against relative rotation of the parts, locking means engaging the outer end of the spindle to hold said parts against separation.
11. A thumb piece for a switch spindle comprising an insulating body, associated means for engaging the switch spindle against relative rotation of the parts, locking means engaging the outer end of the spindle to hold said parts against separation, together with means for sealing said 55 locking means against access.
12. A thumb piece for a switch spindle comprising an insulating body, associated means for engaging the switch spindle against relative rotation of the parts, and locking means passing through the outer end of the thumb piece and engaging the spindle to hold said parts against separation.

In testimony whereof I have signed my 70 name to this specification, in the presence of two subscribing witnesses.

FREDERIC P. GATES.
